United States Patent Office

Des. 204,260
Patented Apr. 5, 1966

204,260

BUCKLE

Murray Moskowitz, Westfield, N.J., assignor to Maidenform, Inc., New York, N.Y., a corporation of New York

Filed Sept. 3, 1965, Ser. No. 86,854

Term of patent 14 years

(Cl. D17—1)

FIG. 1

I claim:

The ornamental design for a buckle, as shown.
